CLAIM

The ornamental design for an electronic display panel,
as shown and described.

DESCRIPTION

FIG. 1 is a top plan view of an electronic display panel
showing my new design, the bottom thereof being plain
and unornamented;

FIG. 2 is a right side elevational view thereof, the left
side thereof being a mirror image of this right side; and
FIG. 3 is a front elevational view thereof, the rear
thereof being a mirror image of this front view.

FIG. 1

FIG. 2

FIG. 3
